UNITED STATES PATENT OFFICE.

DAVID STEVENS, OF SEATTLE, WASHINGTON.

RAIL-ATTACHING MEANS.

1,200,147.

Specification of Letters Patent.

Patented Oct. 3, 1916.

Application filed April 7, 1915. Serial No. 19,681.

To all whom it may concern:

Be it known that I, DAVID STEVENS, a citizen of the United States, residing at Seattle, in the county of King and State of Washington, have invented certain new and useful Improvements in Rail-Attaching Means, of which the following is a specification.

My invention relates to improvements in means for securing rails to plastic cross-ties.

10 An important object of the invention is to provide simple and reliable means for detachably securing the attaching plates with the cross-ties whereby they may be conveniently removed from the cross-tie and moved 15 out of engagement with the rails.

A further object of the invention is to provide means of the above mentioned character, which are simple in construction, inexpensive to manufacture, strong and durable.

Other objects and advantages of the invention will be apparent during the course of the following description.

In the accompanying drawings forming 25 a part of this specification and in which like numerals are employed to designate like parts throughout the same, Figure 1 is a central vertical longitudinal sectional view through one end of a plastic cross-tie showing the rail attaching means in section, Fig. 2 is an enlarged plan view of one attaching plate, Fig. 3 is an edge elevation of the same, and, Fig. 4 is a horizontal sectional view taken on line 4—4 of Fig. 1.

35 In the drawings, wherein for the purpose of illustration is shown a preferred embodiment of my invention, the numeral 5 designates a plastic tie which may be formed of concrete or other cementitious material and 40 which is preferably provided with transverse and longitudinal metallic reinforcing means 6 and 7, as shown. The cross-tie 5 is provided near each end with a recess receiving a vertical casing 8, the bottom of 45 which is closed by a plate 9. The casing 8 has its top flush with the upper surface of the tie 5, and a compressible coil spring 10 is arranged within the casing. This spring 50 is preferably formed of spring steel of 1½ inches diameter and is 3½ inches long. There are preferably 2½ coils in the spring and when a load of 24,400 pounds is applied thereto the spring will compress solid. The ends of the spring are cut horizontally, as

shown. Engaging with the top of the spring 55 10 is a cover-plate or cap 11, extending transversely of the cross-tie 5 and provided with depending ends 12, disposed upon the opposite sides of the cross-tie.

The numeral 13 designates a rail disposed 60 upon the plate 11 and yieldingly supported by the spring 10.

The numeral 14 designates the attaching plates as a whole, each of which embodies a horizontal outer base 15, carrying an inwardly extending portion 16, slightly angularly inclined for engagement with the top of the rail base and provided at its end with a vertical extension or lip 17, to engage with the vertical web of the rail. Each horizontal base 15 is provided with an elongated or approximately elliptical opening 18 extending longitudinally thereof for receiving a vertical bolt 19, extending transversely 70 through the tie and having its head 20 embedded in the bottom thereof and preferably flush with such bottom. The bolt 19 extends through the elongated opening 18 and permits the securing plate 14 being vertically tilted, whereby its upper end will clear 75 the head of the rail upon being removed from or placed in the holding position.

The numeral 21 designates a filler, adapted to fit within the outer portion of the opening 18, and engage with the bolt 19, the 85 same serving to prevent the attaching plate from slipping with relation to the bolt. This filler is held in place by a washer 22, having an eccentric opening 23, receiving the bolt 19, said washer being in turn held 90 in place by a nut 24, having screw-threaded engagement with the bolt. It is thus obvious that the bolts 19 are permanently secured to or embedded within the cross-tie 5 and when it is desired to remove the attaching plates 14, the nuts 24 are unscrewed 95 from their bolts. The fillers 21 are next removed, subsequently to which the plates 14 may be swung upwardly to clear the head of the rail 13 and subsequently wholly removed 100 from the bolts. The reverse of this operation occurs when the plates 14 are being screwed to the bolts.

It is to be understood that the form of my invention herewith shown and described is 105 to be taken as a preferred example of the same, and that various changes in the shape, size, and arrangement of parts may be re-

sorted to without departing from the spirit of the invention or the scope of the subjoined claim.

Having thus described the invention, I claim:—

- 5 The combination with a plastic tie arranged in a substantially horizontal position, of substantially vertical bolts embedded therein and extending upwardly beyond the
10 upper surface of the tie for a substantial distance, rail attaching plates disposed upon the upper surface of the tie and provided with horizontal extensions having elongated openings receiving the upper ends of the
15 bolts in the inner ends thereof, fillers dis-

posed within the outer portions of the elongated openings to contact with the bolts, washers carried by the upper ends of the bolts and having eccentric openings receiving the bolts so that the washers completely 20 span the elongated openings, and nuts having screw-threaded engagement with the upper ends of the bolts to engage the washers, substantially as described.

In testimony whereof I affix my signature 25 in presence of two witnesses.

DAVID STEVENS.
